(57) **CLAIM**

I claim the ornamental design for a dust cassette assembly, as shown and described.

DESCRIPTION

FIG. 1 is a perspective view of the outlet side of the dust cassette assembly

FIG. 2 is a side elevational view of the dust cassette assembly. The opposite side elevational view is a mirror image thereof

FIG. 3 is a front elevational view of the dust cassette assembly. The rear elevational view is a mirror image thereof

FIG. 4 is a top plan view of the outlet side of the dust cassette assembly; and,

FIG. 5 is a bottom plan view of the inlet side of the dust cassette assembly.

The mesh pattern shown in FIGS. 1 and 4 is understood to represent screening and extends uniformly throughout the areas represented.
